DISC SOCKET WRENCH

Benjamin Fedeson, North Tonawanda, N.Y.

Application August 28, 1957, Serial No. 680,859

3 Claims. (Cl. 81—121)

This invention relates to hand held tools, and more particularly to a disc socket wrench.

The disc socket wrench of the invention may be advantageously employed in certain situations where the use of more conventional types of wrenches would be impractical, or impossible. A specific situation would relate to the application or removal of a nut from a stud, wherein the free end of the stud is relatively long, thereby making use of a conventional socket wrench impractical or impossible. A further feature of the disc socket wrench of the invention allows use of the disc socket part of the wrench alone for easy turning of a nut, under certain conditions. Another feature relates to a holding arrangement of the disc socket whereby the disc socket may be easily maintained in engagement with a nut during the turning thereof.

The main object of this invention is to provide a disc socket wrench which may be advantageously employed in certain situations where the use of more conventional types of wrenches would be impractical or impossible.

Another object of this invention is to provide a disc socket wrench wherein the disc socket alone may be used for easy turning of a nut under certain conditions.

Still another object of this invention is to provide a disc socket wrench having holding means whereby the disc socket may be easily maintained in engagement with a nut during the turning thereof.

These and further objects and features of the invention will become more apparent from the following description and accompanying drawing wherein:

Fig. 1 is a perspective view of a disc socket wrench embodying the principles of the invention;

Fig. 2 is a bottom plan view of the disc socket of the wrench shown in Fig. 1;

Fig. 3 is a sectional view as seen from line 3—3 in Fig. 2;

Fig. 4 is the same as Fig. 3 but illustrating the application of the disc socket to a nut threaded upon a stud;

Fig. 5 is a bottom plan view partially broken away in section and illustrating a modified form of the invention;

Fig. 6 is a sectional view as seen along line 6—6 of Fig. 5; and

Fig. 7 is a view showing a modified form of knurl used on the disc socket of Fig. 5.

Referring now to the drawing, the wrench of the invention includes a disc socket member 11 and spanner wrench handle 12. The socket member, which may be formed of metal, is disc-like in form and has a nut-engageable socket recess 13 entering from one face and terminating short of the opposite face so as to provide an inwardly directed flange 14 surrounding an axially arranged bore 16 which opens onto the face 17 of the socket member and which is of larger diameter than a threaded member receiving a nut engageable by the socket member. The flange 14 serves as a holding means whereby the socket member may be maintained against the top of a nut 18, or equivalent. The face of the socket member

on the side of the socket recess 13, has a taper 19 to provide clearance when the socket member 11 engages a nut. A plurality of holes 21 are arranged about the bore 16 parallel with the axis of the socket member, and extend from the tapered surface 19 through the opposite face of the socket member. The holes are arranged in pairs each of the holes of a pair being in diametrical opposition. The periphery of the socket member 11 has serrations 20 or knurls to afford firm gripping of the socket member when the latter is used for manually rotating a nut. It is to be noted, that the diameter of the socket member is substantially greater than the diameter of the socket recess, thereby affording leverage for manually rotating the socket member when it is placed in engagement with a nut.

The spanner wrench handle 12 has a bifurcated end 15 arranged to provide clearance about a stud when the handle is used upon the socket member 11. Extending from the bifurcated end of the handle 12 are protrusions, or pin members 22 adapted for engaging oppositely disposed holes 21 of the socket member 11.

As seen in Fig. 4, the socket member 11 may be placed upon the nut 18 mounted upon a stud 23 the free end of which extends a substantial distance beyond the top of the nut 18. Such a use of the wrench of the invention would not be possible with conventional socket wrenches due to the length of the stud 23. In such position of the socket member 11, the nut 18 may be rotated by hand, or if this is too difficult, the wrench handle may be affixed to the socket member by placing the pin members 22 into holes 21 of the socket member. As the nut 18 is rotated for removal from the stud 23, the flange 14 will hold the socket member in position upon the nut so that operative engagement therewith will not be disrupted.

From the foregoing it will be seen that a disc socket wrench according to the invention may be used either for manually turning a nut upon a threaded member, or for using a wrench handle therewith if necessary to overcome rotational resistance of the nut. It will be further seen that the socket member may be used where the use of conventional-type socket wrenches would be impractical, such as when the nut is mounted upon a long stud, or equivalent. In addition, it will be seen that the holding means i.e., flange 14, will maintain the socket member in engagement with the nut during operation thereupon, a convenience which is not always afforded by wrenches of the prior art.

Referring to Figs. 5 to 7, a modified form of wrench is shown wherein a socket member 24, the body of which is preferably formed of a plastic material such as cellulose acetate butyrate, has a metallic socket insert 26 axially arranged as shown. The body of the socket member 24 has an axial bore 27 about which is arranged a flange 28 adapted to overlap the inner diameter of the socket insert 26, to act as a holding means in the manner of flange 14 in the previously described embodiment.

The socket insert has a straight knurl 26a arranged about its outer periphery, and has a circumferential rabbet 29 at one end thereof. A plurality of through holes 31 are arranged in the socket member for engagement by the pin members 22 of the wrench handle 12 if the latter is to be used with the socket member 24. The outer periphery of the socket member 24 is knurled at 25 to afford a better gripping surface when the socket member is placed upon a nut for manual rotation.

The body of the socket member 24, being plastic, will be molded about the metallic socket insert 26, the latter being held in position between the flange 28 and the plastic material which enters the circumferential rabbet 29. The knurled surface of the metallic insert will lock

the insert within the socket member. Instead of straight knurls on the outer surface of the metallic socket insert 26, diamond shaped protrusions 32 may be used for locking the insert within a socket member as illustrated in Fig. 7. In such an arrangement, it would not be necessary to provide a circumferential rabbet such as rabbet 29, since the diamond shaped protrusions will prevent axial or rotational movement of the insert relative to the socket member 24.

The use of the modified socket member 24 for operation upon a nut, is identical to that of the socket member 11, the main difference being in the manner of fabrication, and the material used.

From the foregoing it will be seen that the disc socket wrench of the invention may be conveniently used where it would be impractical or impossible to use conventional type socket wrenches.

The foregoing description has been given in detail without thought of limitation since the inventive principles involved are capable of assuming other physical embodiments without departing from the spirit of the invention and the scope of the appended claims.

What is claimed is:

1. In a disc socket wrench, a disc-like member having a body formed of a plastic material with a recess entering from one face and terminating short of the opposite face to provide an inwardly directed flange surrounding an axially arranged bore, and a metal insert in said recess and adapted to provide the peripheral surface of a nut-engageable socket, said flange overlying one end of the insert and extending inwardly thereof to provide the radial surface of said nut-engageable socket, said insert having serrations on its outer periphery in relative nonrotative engagement with said body.

2. In a disc socket wrench, a disc-like member having a body formed of a plastic material with a recess entering from one face and terminating short of the opposite

face to provide an inwardly directed flange surrounding an axially arranged bore, and a metal insert in said recess and adapted to provide the peripheral surface of a nut-engageable socket, said flange overlying one end of the insert and extending inwardly thereof to provide the radial surface of said nut-engageable socket, said insert having parallel serrations on its outer periphery in relative nonrotative engagement with said body and being formed to provide a circumferential rabbet engaging said body at the end of said insert opposite to that adjacent the inwardly directed flange.

3. In a disc socket wrench, a disc-like member having a body formed of a plastic material with a recess entering from one face and terminating short of the opposite face to provide an inwardly directed flange surrounding an axially arranged bore, and a metal insert in said recess and adapted to provide the peripheral surface of a nut-engageable socket, said flange overlying one end of the insert and extending inwardly thereof to provide the radial surface of said nut-engageable socket, said insert having diamond-shaped serrations on its outer periphery in relative nonrotative engagement with said body.
